UNCURLING GUIDE FOR SEWING MACHINES

Hans Hacklander, Linden, N. J., assignor to The
Singer Manufacturing Company, Elizabeth,
N. J., a corporation of New Jersey

Application August 4, 1942, Serial No. 453,493

7 Claims. (Cl. 112—20)

This invention relates to fabric uncurling and guiding devices and more particularly to that type of uncurling and guiding devices used on hosiery seaming sewing machines.

The type of hosiery which is now in vogue has the heel and toe as well as the top or garter portions reenforced with additional interwoven threads, and thus it occurs that these sections of the hose are of heavier gauge than the remaining sections. In the past, difficulty has been experienced in uncurling, guiding and seaming the edge portions of hosiery having a variable gauge. Whenever the fabric changes from a heavy to a thin gauge, while passing through an uncurler, the thin gauge portion thereof tends to drop out of the uncurler as the heavy portion of the fabric has spread the uncurling wings of the uncurling guide away from the central fabric-guiding plate, so that they cannot engage the thin fabric sections and hold them against dropping below the needle path. Whenever the material thus drops below its normal level the needle will either miss the edge of the work or it will penetrate the work at a point so close to the edge that a weak seam will result. Among those skilled in the hosiery seaming art the above described defect is referred to as a drop-out."

It has been found that the above described "drop-outs" may be obviated if the work is raised slightly just before the relatively thick portion of the stocking terminates and the thin portion is encountered by the uncurler. Thus, by raising the work, the needle will be caused to penetrate the work at a substantial distance from the edge thereof. Also, it has been found that one of the most effective ways of raising the work is to provide an uncurling device which is free to rise in response to an upward force exerted by the free or unseamed portions of the work under skillful handling by the operator, thereby permitting the work to be fed to the feed cups at a higher level than normal.

It is therefore an object of the present invention to provide a simple and inexpensive uncurling guide having at least a portion thereof shiftable in response to an upward force as exerted by the unseamed portions of the work.

With these and other objects in view, as will hereinafter appear, the invention consists in the devices, combinations and arrangements of parts described in connection with the accompanying drawing, which illustrates a preferred embodiment of the invention and in which—

Fig. 1 is a side elevation of the present invention.

Fig. 2 is a front elevation of the present invention partly in section.

Fig. 3 is a vertical section of the present in-

vention taken substantially along line 3—3 of Fig. 2.

Fig. 4 is a side elevation of the present invention as applied to a cup-feed hosiery seaming machine with the outer feed-cup removed.

Fig. 5 represents a portion of a stocking. In the embodiment of the invention selected for illustration, my improved uncurling guide is shown as applied to a so-called cup-feed sewing machine having a standard 10 and an overhanging bracket 11 from which depends the uncurling guide and an outer feed-cup which is not shown herein. An inner feed-cup 12 is supported by the standard 10 and it is adapted to help in advancing the work past the stitching mechanism which includes a needle 13 and other devices not shown. For a detailed description of the cup-feed machine shown in the drawing, reference may be had to my Patent No. 2,277,970, dated March 31, 1942.

One modification of the present invention is illustrated as comprising a central shank portion 14 having formed thereon and disposed transversely thereof two apertured cross-bars 15 and 16 for receiving the threaded pins 17. Cooperating with the shank 14 are two presser-members 18 pivotally secured thereto by means of the pins 17 passing through the apertured cross-bars 15 and 16. These presser-members 18 terminate in uncurling plates 19 which are urged toward each other by means of the coil-spring 20. This spring 20 passes through an aperture 21 provided in the shank 14 to bear against the recessed bosses 22 of the presser-members 18. Each uncurling plate 19 is formed with the usual uncurling protuberance 23 located upon the entrance end thereof.

The shank portion 14 is pivotally secured to the overhanging head 11 of the machine by means of a latching device which is illustrated but not described in this case. For a more detailed description of this latching device, reference may be had to my Patent No. 2,256,672, dated September 23, 1941.

45 The lower portion of the shank 14 terminates in a bifurcated socket comprising the two parts 24 and 25 which slidably receive therebetween a fabric guiding plate 26. This guiding plate 26 is carried within the lower portion of the shank 50 14 by means of two pins 27 the ends of which are secured each within a respective one of the parts 24 and 25. Each pin 27 passes through a respective one of the elongated apertures 28 provided in the plate 26. Mounted within and 55 transversely of the plate 26 is a gauge pin 29 which extends from each face thereof to be received within each of the elongated apertures 30 provided in the presser-members 18. The purpose of this pin 29 is to engage the edges of the 60 hosiery blank and thereby limit the elevation at

which the blank is delivered to the feed-cups and sewing needle 13.

Between the upper portions of the parts 24 and 25 is carried a weak spring 31 of which its upper end is received in a vertical aperture 32 and its lower end engages the top of the plate 26 thereby to constantly urge the plate 26 downwardly.

Fig. 4 illustrates a hosiery blank 33 being delivered to the uncurler in the usual manner, and the line 34 represents the normal level of the work. However, as hereinabove noted, it sometimes becomes desirable to increase the "bite" of the needle as by raising the normal feed level of the work. To raise the feed level, when using the present device, the operator need only raise the unseamed portion of the hosiery blank 33 and the upward force of the edges of the hosiery blank upon the guide-pin 29 will in turn raise the plate 26 against the action of the spring 31 which latter is weak enough to be overcome by such force. By replacing the spring 31 with other springs having various strengths the operator may adjust the uncurler to suit the various sewing conditions.

Fig. 5 illustrates a portion of a stocking and the heavily shaded section 35 represents the reinforced heel portion and the lightly shaded section 36 represents the normal or thin gauge portion of the stocking. As hereinabove noted the "drop-outs" occur during the time when the thick section 35 of the stocking passes through the uncurler and it is followed directly by the thin section 36. It will be understood, therefore, from the above description, that by using the present uncurler the "drop-out" may be obviated by merely raising the free or unseamed portions of the work thereby raising the guide-plate 26 and gauge-pin 29 to permit the work to be fed to the feed-cups at a higher level than normal.

Having thus set forth the nature of the invention, what I claim herein is:

1. A fabric uncurling and guiding device for sewing machines, comprising, a central shank, a pair of presser-members cooperating with and secured directly to said central shank, a fabric guiding plate carried by the lower portion of and disposed in substantially the same plane as said central shank, a spring element associated with said guiding plate to spring bias the same away from said central shank, and means to permit a limited amount of relative rectilinear movement between said central shank and said guiding plate.

2. A fabric uncurling and guiding device for sewing machines, comprising, a central shank, a pair of presser-members cooperating with and secured directly to said central shank, a fabric guiding plate carried by the lower portion of and disposed in substantially the same plane as said central shank, gauging means carried by said guiding plate for contacting and gauging the height of a fabric edge, a spring interposed between said guiding plate and said central shank for spring biasing said guiding plate away from said central shank, and means to permit a limited amount of relative movement between said central shank and said guiding plate.

3. A fabric uncurling and guiding device for sewing machines, comprising, a central shank, a pair of presser-members pivotally secured directly to said central shank, a fabric guiding plate of which the upper portion is slidily

received within the lower portion of said central shank, a gauge pin carried by and disposed transversely of said guiding plate for contacting and gauging the height of the edges of a fabric, the opposite ends of said guide pin being received by elongated apertures provided in said presser-members, a spring element associated with said guiding plate to spring bias the same away from said central shank, and means carried by said central shank to limit the sliding movements of said guiding plate relative to said central shank and said presser-members.

4. A fabric uncurling and guiding device for sewing machines, comprising, a central shank, a pair of presser-members pivotally secured directly to said central shank, a fabric guiding plate, the lower portion of said central shank being bifurcated to slidily receive the top portion of said guiding plate, a spring element associated with said guiding plate to spring bias the same away from said central shank, and means carried by said central shank to limit the sliding movements of said guiding plate relative to said central shank and said presser-members.

5. A fabric uncurling and guiding device for sewing machines, comprising, a central shank, a pair of presser-members carried directly upon said central shank, a fabric guiding plate disposed in substantially the same plane as said central shank, the lower portion of said central shank being bifurcated to slidily receive the top portion of said guiding plate, at least one pin secured to said central shank and extending through an elongated aperture provided in said guiding plate, a spring element associated with said central shank and engaging said guiding plate so as to spring bias the guiding plate away from said shank, and fabric gauging means carried by said guiding plate.

6. In a fabric uncurling device for sewing machines, a pair of spring-pressed presser-members, fabric uncurling elements carried upon said presser-members, a fabric guiding plate disposed between said presser-members, a gauge pin carried by and disposed transversely of said guiding plate, the opposite ends of said guide pin being received by elongated apertures provided in said presser-members, means upon which said presser-members and said guiding plate are mounted, and means to permit said guiding plate to shift lengthwise of itself and relative to said uncurling elements.

7. A fabric uncurling and guiding device for sewing machines, comprising, a central shank, a presser-member pivotally mounted upon each of the two opposite sides of said central shank, a fabric guiding plate disposed in substantially the same plane as said central shank, the lower portion of said central shank being bifurcated to slidily receive the top portion of said guiding plate, a pair of spaced pins secured within said central shank and each extending through an elongated aperture provided in said guiding plate, a spring interposed between the top portion of said guiding plate and said central shank so as to spring bias the guiding plate lengthwise of itself and away from said shank, and a gauge pin carried by and disposed transversely of said guiding plate for contacting and gauging the height of a fabric, the opposite ends of said gauge pin being received by elongated apertures provided in said presser-members.

HANS HACKLANDER.
